UNITED STATES PATENT OFFICE.

HENRY A. THEXTON, OF MINNEAPOLIS, MINNESOTA, ASSIGNOR TO THEXTON MANUFACTURING COMPANY, OF MINNEAPOLIS, MINNESOTA, A CORPORATION OF MINNESOTA.

DOOR LATCH AND LOCK.

Application filed July 20, 1920. Serial No. 397,626.

To all whom it may concern:

Be it known that I, HENRY A. THEXTON, a citizen of the United States, residing at Minneapolis, in the county of Hennepin and 5 State of Minnesota, have invented certain new and useful Improvements in Door Latches and Locks; and I do hereby declare the following to be a full, clear, and exact 10 description of the invention, such as will enable others skilled in the art to which it appertains to make and use the same.

My invention has for its object to provide an improved door latch and lock; and, to 15 this end, my invention consists of the novel 15 devices and combinations of devices herein-after described and defined in the claims.

The accompanying drawings illustrate my invention in its preferred form.

In said drawings, like notations referring 20 to like parts throughout the several views,

Fig. 1 is a view in side elevation showing 25 my improved latch and lock in working position, in respect to a door and door post, with portions of the door and post broken away;

Fig. 2 is a view of the same parts as shown 30 in Fig. 1, partly in side elevation and partly in vertical section, with some portions broken away;

Fig. 3 is a horizontal longitudinal section 35 on the line 3—3 of Figs. 1 and 2;

Fig. 4 is a vertical cross section on the line 4—4 of Figs. 1 and 2;

Fig. 5 is a vertical cross section on the line 35 5—5 of Fig. 3;

Fig. 6 is a view, chiefly in horizontal section, taken lengthwise through the rotary tumbler of the lock in the plane of the key seat, when the key is seated therein in unlocking position, and which section extends 40 through the adjacent parts of the casing on an irregular line;

Fig. 7 is a perspective view, partly in section, showing the tumbler seat and adjacent 45 portions of the casing, some parts broken away;

Fig. 8 is a cross section of the lock on the line 8—8 of Fig. 6, with the parts in the same position shown in Fig. 6;

Fig. 9 is a plan view of the locking tumbler 50 detached;

Fig. 10 is a perspective view of a part of

the door with the base plate section of the lock casing in position thereon but with the face plate section of the casing and spring-pressed bolt removed;

Fig. 11 is a perspective view showing part of the door post and the base section of the two-section keeper shown in Figs. 1, 2 and 3;

Fig. 12 is a perspective view of the other 60 or catch section of said two-piece or two-section keeper detached;

Fig. 13 is a perspective view of the face plate or cover section of the latch and lock casing detached; and

Fig. 14 is a perspective view of the hollow bolt detached and turned over on its side, so as to look into the interior thereof through its open back.

The numeral 15 represents a part of the 70 door, the hinges (not shown) of which are assumed to be applied at the left side of the same. The numeral 16 represents the adjacent or right-hand door post. The numerals 17 and 18 represent, respectively, the 75 base plate and the face plate or cover sections of the two-part lock casing, shown assembled in Figs. 1, 2 and 3, and shown separated from each other in Figs. 10 and 13. The said base plate 17 and face or cover 80 plate 18 are adapted to be secured together and to the door 15 by screws 19 working through registering holes in the two plates, when the parts are in working position, and the face or cover plate 18 is of such shape 85 as to afford a seat for a hollow bolt 20, when said two plates are so secured in working position.

The base plate 17 is provided with a 90 spring base or base of resistance 21 and a bolt stop or abutment 22, which parts are shown as formed by stamping them out of a body of the bolt plate and turning them inward, until they stand at right angles to the body of the base plate and parallel to each other, as best shown in Fig. 10. The hollow bolt 20 is provided with a corresponding spring base or base of resistance 23, which is shown as formed by pressing the same out from the face of the hollow bolt and turning the same inward until it stands at right angles thereto, as best shown in Figs. 3 and 14. The numeral 24 represents a coiled spring which, when com-

pressed, is adapted to be seated between the base of resistance 21 projecting outward from the base plate 17 of the casing and the base of resistance 23 projecting inward from the face of the hollow bolt 20, when suitably compressed to the requisite tension, as best shown in Figs. 2 and 3, and will then, thereafter, tend to move the bolt outward to its limit for bringing its bevel faced nose into latching position. This limit is made a variable one, by providing in the hollow bolt 20 a series of stop seats 25, shown as formed by registering slots cut out in the top and bottom walls of the hollow bolt 20, and into any desired one of which seats 25 may be placed a hook headed piece 26, which is of a length to pass through the bolt and depend therefrom, with its lower end in position to serve as a trigger for the bolt, while its body portion within the bolt will be in position to contact with the abutment 22 projecting from the base plate 17 of the casing, and thereby limit the travel of the bolt, under its actuating spring 24. The bolt 20 is shown as provided with three of these seats 25 for the combined stop and trigger 26; and hence, three different limits may be set for the travel of the bolt, according to which of the three seats 25 is selected for said combined stop and trigger. Compensation for shrinkage of the door or door frame relative to each other is, therefore, available directly in the latch and lock itself, by simply making the necessary adjustments of the said combined stop and trigger 26 to properly vary the travel of the bolt, under the action of its spring 24.

The numerals 27 and 28 represent, respectively, the base plate and the catch plate of the two-part or two-section keeper, for co-operation with the bolt of the latch and lock. The base plate 27 of the two-part keeper is shown as provided with vertical slots 29, for adjustably securing the same to the door post 16 by screws 30 working with their stems extending through the said slots, as shown in Fig. 11. The said section 27 is provided with end flanges 31, conveniently formed by turning over its end portions, and is also shown as provided with a stop flange 32 projecting from its outer edge. The catch plate 28 is of the proper shape to receive the end of the bolt 20 and is provided with end flanges 33, adapted to engage the guide flanges 31, and has a closed inclined back adapted to abut the stop flange 32 projecting from the section 27, when the parts are in proper working position, relative to each other, as shown in Figs. 1, 2 and 3. The bolt 20 is shown as provided with a screw-threaded handle stem 34, adapted to be engaged by the interior thread of a handle 35 which, when the parts are in working position, projects

through the base plate 17 of the casing and a suitably elongated slot 36 in the door 15, as best shown in Fig. 3, for the operation of the bolt from the inside of the door.

The hollow bolt 20 is shown as provided on the rear end of its face with an inwardly extending flange 37 adapted to engage with any desired one of several notches in a lock rib 38 extending lengthwise of and projecting from a rotary locking tumbler 39 suitably seated in a bearing block 40 fixed to the face plate 17, as best shown in Fig. 10. The rear end of this tumbler 39 projects outward through the bearing block 40 and is shown as provided with a handle head 39^a. This tumbler 39 is provided with a key-way 41 extending lengthwise thereof in the plane of its axis, as best shown in Fig. 9 of the proper shape to receive through its outer end a controlling key 42, as best shown in Fig. 6. In other words, the key 42 is a flat key and the key-way 41 is adapted to receive the same. The block 40, in which the tumbler 39 is seated, is provided with a spring-seated locking detent 43, as best shown in Figs. 3 and 6, the inner end of which is adapted to engage with a socket 44 formed in the periphery of the tumbler 39 and opening into the key-way 41. The key 42 is provided with two diametrically opposite inclined faced noses 45 interchangeably adapted to engage the inner end of the detent 43, when the key is pushed inward to its limit within its seat in the tumbler 39, and, by the camming action of the nose on the end of the detent 43, to force the latter outward and thereby release the tumbler from its locked position. The key 42 is provided with a pair of diametrically opposite notches 42^a on each of its opposite edges; the tumbler 39 is provided with a corresponding pair of annular grooves 39^b; and the block 40 is provided with a pair of corresponding pins 40^a projecting radially inward from the tumbler seat, with the two in line with each other and slightly staggered circumferentially, in respect to the locking detent 43, as best shown in Figs. 6 and 7, and which pins 40^a are adapted to engage the annular grooves 39^b of the tumbler and the notches 42^a of the key 42, thereby permitting the key and the tumbler to be rotated together by the key into unlocking position. The reason why the pins 40^a are staggered, in respect to the locking detent 43, is to permit the key 42 to be inserted into its seat. It is possible to place the tumbler 39 into its seat within the bearing block 40, for the reason that the key-way 41 is first formed open at its top, for the full length of the tumbler shaft, and is of such size in cross section that, when the tumbler 39 is brought to such position that the key-way 41 will register or align with the pins 40^a, the tumbler can be pushed into its seat and

is there secured by the body plate of the lock rib 38 applied to the idle end portion of said key-way. The notched lock rib 38 is located circumferentially ninety degrees apart from the detent socket 44 or top of the key-way 41, and, after the key has been inserted into unlocking position, as shown in Fig. 6, it is given a quarter turn, at the end of which, the outermost lug of the lock rib will come up against a banking or stop shoulder 40^b of the bearing block 40 and stop the further rotation of the key and the tumbler, and when this occurs, the lock rib 38 will have become disengaged from the flange 37 of the hollow bolt 20 and the bolt will be unlocked. The number of notches in the lock rib 38 correspond to the number of seats 25 for the combined stop and trigger 26 carried by the bolt 20; and hence, in all of the adjustments of said combined stop and trigger, the flange 37 of the hollow bolt will engage the proper corresponding notch of the lock rib 38, when the bolt is in locking position. The tumbler 39 can be turned into locking position by hand, and, when in this position, the lock rib 38 will come up against a vertical banking or stop shoulder 40^c of the bearing block 40 (shown in Fig. 7). When the tumbler has been disengaged from the locking detent 43 by the key 42 and turned thereby into its unlocked position, the detent 43 will engage with a concave or cam action seat 39^c formed on the periphery of the tumbler (see Fig. 8) ninety degrees apart from the locking detent socket 44 therein. This same unlocking rotary motion of the tumbler, effected by the key 42, released the lock rib 38 from the flange 37 of the hollow bolt, as before noted: and the spring-actuated bolt 20 will then be in position for usage as an ordinary spring latch. The inclined or cam-acting surface of the seat 39^c, then engaged by the end of the detent 43, will afford enough resistance against any sliding motion of the bolt to prevent it from jarring loose from its door-latching position, or otherwise stated, any shaking of the door, however produced, but this resistance is not great enough to prevent the bolt from being moved by hand, or the camming action of its beveled outer end, when the latter strikes the edge of the catch section 28 of the keeper, under the closing motion of the door.

For the same reason, to wit: the slight resistance afforded by the cam-acting surface of the seat 39^c, when engaged by the detent 43, the tumbler can be rotated into its locking position by hand, thus enabling the bolt 20 to be locked in its door-closing position, without the use of the key. The bolt cannot, however, be released from its locking position without the use of the key 42. Different locks and the keys for the same will have the annular grooves 39^b of their respec-

tive tumblers and the corresponding notches 43 of their respective keys differently located and the pins 40^a in the bearing seat of the tumbler will be correspondingly located in different positions, so that only one key 70 will fit one lock.

From the foregoing description, it must be obvious that my mechanism is adapted to be used, either as an ordinary spring latch or as a lock, as occasion may demand and 75 that it is interchangeably right or left, so as to apply to doors hinged at either of the two opposite edges or to either of the two opposite sides of a door and its co-operating door post. It has also been noted that the throw of the bolt may be adjusted to compensate for shrinkage of the door and post relative to each other. From the fact that the base section 27 of the two-part keeper, made up of the sections 27 and 28, is provided with the slots 29 through which its securing screws 30 are applied, it follows that the keeper may be adjusted on a post to compensate for the sagging of the door or the post, relative to each other. 90

The face plate or cover section 18 of the casing is so shaped, in respect to the base plate 17 of the casing and the parts carried by the casing made up of these sections, that the downwardly projecting end of the combined stop and trigger 26, carried by the bolt 20, can only be taken hold of by the fingers of a person's hand, underreaching the lower edge of a downwardly projecting part 18^a of its face wall. In other words, this downwardly projecting portion 18^a of the face wall of the cover section 18 extends for the full length of the possible travel of said combined stop and trigger 26 with the bolt 20, and, at all times, will guard said trigger 105 from being reached by the horns of cattle seeking to open the door. Persons, familiar with the handling of cattle in barns, are well aware of the fact that in nearly every herd, there is likely to be one or more animals who 110 get wise enough to a lock to open it with their horns, if they can reach the latch thereby, much in the same way as such so-called "wise cows" will release themselves from their holding stanchions. When my mechanism is used on cattle barns, it is usually applied to the inside of a door and door post and the said guarding portions 18^a of the face of the cover section 18 of the casing then becomes effective to prevent the bolt 120 from being opened by the cattle. 115

Although capable of the numerous functions above stated, it must be obvious that my mechanism is extremely simple and cheap to make. Most of its parts can be 125 stamped up out of sheet metal.

The practicability and utility of my improved latch and lock has been demonstrated by the actual commercial usage of the same.

It will be understood, of course, that more 130

or less of the details could be changed without departing from the spirit of the invention.

What I claim is:—

1. A lock having in combination a rectangular boxlike bolt of sheet metal, a boxlike casing enclosing the same and having a tongue bent up from one side thereof forming a stop for the bolt, said bolt having spaced tongues pressed therein at opposite sides forming slots, and an adjustable stop and trigger member adapted to be received in any one of said slots and adapted to contact with said stop member formed in the casing.

2. In a door latch, the combination with a spring-pressed bolt and a casing for the same, of a stop abutment on the casing, a stop on the bolt for co-operation with said abutment, and a series of interchangeably usable seats in said bolt for said stop, whereby the throw of the bolt may be varied, at will, substantially as described.

3. In a door latch, the combination with a spring-pressed bolt and a casing for the same, of a stop abutment on the casing, a series of interchangeably usable stop seats in said bolt, and a combined bolt trigger and stop insertable into any of said seats, according to the throw desired and projecting into position to be used as a trigger to retract the bolt against the tension of its spring, substantially as described.

4. In a door latch, the combination with a spring-pressed bolt, of a casing made up of a base plate section carrying the bolt and its controlling devices, and a face plate section adapted to be separably secured to said base plate section and to encase the bolt in either of two endwise reversed positions of the bolt and base plate, whereby the latch is rendered interchangeably right or left, as may be desired, substantially as described.

5. In a door latch, the combination with a spring-pressed bolt and a rotary holding tumbler, of co-operative engaging parts on the bolt and the tumbler adapted to be brought into engagement by rotating the tumbler when the bolt is at the limit of its spring-pressed throw to hold the same in its latching position, substantially as described.

6. In a door latch, the combination with a spring-pressed bolt, of means adjustable, at will, for varying the throw of the bolt, a holding tumbler, and co-operative engaging parts on the bolt and the tumbler, one set of which is in a series spaced apart from each other lengthwise of the element carrying the same, whereby the said tumbler may be made to hold the bolt in its latching position in any of its predetermined limits of travel, substantially as described.

7. In a door latch, the combination with a variable throw spring-pressed bolt having

a holding flange, of a rotary holding tumbler having a holding rib with a series of notches for interchangeable engagement with said flange of said bolt according to the length of the bolt's throw to hold the bolt in its latching position, substantially as described.

8. In a door lock, the combination with a spring-pressed bolt and a casing, of a rotary locking tumbler in said casing provided with a key seat extending centrally lengthwise thereof and having on its periphery a seat extending into the keyway for receiving a locking detent, and a spring-acting locking detent in said casing adapted to engage said socket to hold the tumbler and bolt in their locked position and which detent is subject to a camming action from the key to release the tumbler and latch from their locked position, substantially as described.

9. In a door lock, the combination with a spring-pressed bolt and a casing, of a rotary locking tumbler in said casing provided with a key seat for a flat key extending centrally lengthwise thereof and having on its periphery a seat extending into said key-way for receiving the end of a locking detent in said casing adapted to engage said socket, and a flat key having at its entering end two oppositely located noses with inclined faces adapted to engage interchangeably with said detent under a camming action to release the tumbler, substantially as described.

10. In a door lock, the combination with a spring-pressed bolt and a casing, of a rotary locking tumbler in said casing provided with a key seat for a flat key extending lengthwise thereof, and a series of annular grooves on its periphery, of radially disposed pins in the casing, the inner ends of which project into said grooves of said tumbler, a locking member in said casing engageable with said tumbler to hold the parts in their locked position, and a flat key provided with a pair of diametrically opposite projecting noses adapted to engage with said member under a camming action to release the same and provided with notches corresponding in number and spacing with said grooves and pins, whereby, when the key is seated in the tumbler, it may be made to rotate the same, substantially as described.

11. In a door lock, the combination with a spring-pressed bolt and a casing for the same, of a rotary locking tumbler in said casing, co-operative engaging parts on the bolt and tumbler adapted to be brought into engagement by rotating the tumbler when the bolt is at the limit of its spring-pressed throw to hold the same in its latching or locking position, a locking detent in said casing adapted to engage a seat in the periphery of said tumbler to hold the parts in their locked position, which tumbler is provided

with a key seat extending centrally lengthwise thereof radially tapped by said detent seat, and a key insertable into seat and adapted to operate on said detent with a camming action to release the said parts from their locked position, substantially as described.

12. In a loor latch and lock, the combination with a variable throw spring-pressed bolt having a holding flange, of a rotary holding tumbler having a holding rib with a series of notches for interchangeable engagement with said bolt flange, according to the predetermined throw of the bolt, a resiliently actuated locking detent, the inner end of which is engageable with a seat in said tumbler to hold the parts in their locked position, a flat key, and a correspondingly shaped keyway extending lengthwise of said tumbler which key is provided with two diametrically opposite inclined faced noses adapted to act on the said detent with a camming action to release the parts from their locked position, substantially as described.

13. In a door latch and lock, the combination with a variable throw spring-pressed bolt having a holding flange, of a rotary holding tumbler having a holding rib with a series of notches for interchangeable engagement with said bolt flange, according to the predetermined throw of the bolt, a spring-acting locking detent, the inner end of which is engageable with a seat of said tumbler to hold the parts in their locked position, a flat key, a correspondingly shaped key-way extending lengthwise of said tum-

bler and tapped by said detent seat and which key is provided with two diametrically opposite inclined faced noses adapted to act on the said detent with a camming action to release the parts from their locked position, whereby said tumbler may be rotated into a position to disengage the holding rib from the bolt flange, and an inclined wall or cam-faced socket in said tumbler's face adapted to be engaged by said spring-actuated detent when said tumbler is in its bolt-releasing position, whereby the bolt will operate as an ordinary spring-pressed latch, substantially as described.

14. A horn-proof door latch comprising a spring-actuated bolt and trigger for moving the bolt against the tension of a spring, of a casing for said bolt having means affording access to the trigger by the fingers of a person's hand, and extending down in front of said trigger and forming a guard to prevent access thereto by an animal's horns.

15. A horn-proof door latch comprising the combination with a spring-actuated bolt provided with a trigger extending downward through the bottom of the same, of a two-section casing, the outer or cover member of which is provided with a downwardly projecting face plate affording access to the trigger by the fingers of a person's hand under-reaching said face plate, but always guarding the trigger against access thereto by an animal's horns, substantially as described.

In testimony whereof I affix my signature.
HENRY A. THEXTON.
